P. SELTNER.

SHOWER ATTACHMENT FOR BATH TUBS.

APPLICATION FILED FEB. 7, 1916.

1,193,302.

Patented Aug. 1, 1916.

INVENTOR

Peter Seltner

ATTORNEY

UNITED STATES PATENT OFFICE.

PETER SELTNER, OF McMECHEN, WEST VIRGINIA.

SHOWER ATTACHMENT FOR BATH-TUBS.

1,193,302.

Specification of Letters Patent. Patented Aug. 1, 1916.

Application filed February 7, 1916. Serial No. 76,807.

To all whom it may concern:

Be it known that I, PETER SELTNER, a citizen of the United States of America, and resident of McMechen, county of Marshall, and State of West Virginia, have invented certain new and useful Improvements in Shower Attachments for Bath-Tubs, of which the following is a specification.

This invention relates broadly to shower attachments for bath-tubs, and it has for its primary object to provide a simple and comparatively inexpensive shower device which may be readily applied to and removed from the cock of a bath-tub as occasion may require.

A further object of the invention is to provide a device of the character mentioned which is supported by the bath-cock in an upright position and which has the shower-ring thereof foldable to an out-of-the-way position when not in use. And a still further object is to provide a device of the character mentioned the shower-ring of which is adjustable to any desired elevation to suit the height of the user.

With these and other objects in view, the invention resides in the features of construction, arrangement of parts and combinations of elements which will hereinafter be fully described, reference being had to the accompanying drawings, in which—

Figure 1 is a side elevation of the invention applied to a bath-cock of an ordinary type; Fig. 2 is a front elevation of the same; Fig. 3 is an enlarged vertical section of the cylinder illustrating the telescopic feature of the device, including the water-pressure-operated piston; Fig. 4 is an enlarged top plan view of the disk-like hinge-valve; Fig. 5 is an enlarged face view of the hand-operated controlling valve; Fig. 6 is an enlarged section of the hot and cold water inlets of the bath-cock, showing the supporting member seated thereon; Fig. 7 is an enlarged detail section of the controlling valve; Fig. 8 is a side elevation of the hinge valve; and Fig. 9 is an enlarged detail section of the mouth of the bath-cock and of the coupling means employed.

Referring to said drawings, in which like designating characters distinguish like parts throughout the several views—1 indicates generally a bath-cock of an ordinary type mounted within a bath-tub 2, said cock having the usual tubular inlets 3 for hot and cold water and an interiorly threaded out-

let or mouth 4. The parts composing the present invention are coupled to and supported by the bath-cock 1.

Referring specifically to Figs. 1 and 2 of the drawings, 5 indicates a short upright tube disposed between the two inlets 3 of the bath-cock, and connected at its lower end to one end of a U-shaped coupling member or union 6, the opposite end of which is disposed in vertical alinement with the mouth 4 of said cock. A nipple 7 has its upper and lower ends respectively seated within said mouth 4 and the alined end of the union 6, glands 8 and 9 being provided for forming tight joints, as shown. Connected to the upper end of the tube 5 by means of a union 10 is an upright tube 11, and disposed on said tube 5 in underlying abutting relation to the union 10 is the central portion of a bow-shaped support or saddle 12 the under faces of the end portions of which are shaped to conformably seat upon the inlets 3 of the bath-cock, as is most clearly shown in Fig. 6, said support 12 being designed to sustain the major portion of the weight of the parts composing the invention, thus relieving the mouth portion of the cock from performing that duty.

The pipe 11 is of suitable length and has a hand-operated three-way control valve 13 mounted upon its upper end. Coupled to the upper end of said valve 13 is the lower end of a tube 14 which, on account of its peculiar character, will hereinafter be termed a cylinder. Said cylinder has telescopically received therein the lower portion of a tube 15 of materially smaller diameter than said cylinder, said tube 15 carrying upon its lower end an encircling piston 16. Connected to the upper end of the tube 15 by means of an elbow coupling 17 is one end of a short horizontally disposed tube 18 to the opposite end of which is connected one arm 19 of a hinge valve 20. Connected to the opposite arm 21 of said hinge valve is a tubular arm 31 which carries upon its outer end a circular perforated shower ring 22 of a common form.

The three-way valve 13 has a laterally disposed arm 23 having an outlet passage therethrough, as shown in Fig. 7, said arm being designed to receive thereon one end of a flexible hose 24 having a spray nozzle 25 on its opposite end, as shown in Fig. 2. As is obvious, the moving part 13 of said valve 13 may be turned from the closed po-

sition shown in Fig. 7 to either a position wherein water is supplied both to the spray nozzle 25 and to the shower ring 22 or to the latter alone, according to the direction of movement of said part 13', the latter being provided with a straight diametrical passage 26 therethrough and also with a radially disposed passage 27 which communicates at its inner end with said passage 26.

19 When in its closed position the valve 13 permits the water to drain from the superposed parts through the hose 24 and spray nozzle 25.

When a full head of water is admitted to the cylinder 14 by the opening of valve 13, the pressure of the water acts upon the piston 16 carried by tube 15, which normally occupies the position indicated by dotted lines in Fig. 3, and said piston and tube are thereby elevated to the full line position shown in said figure. As is obvious, the upward movement of the tube 15 may be stopped at any desired point by setting thereagainst a set-screw 28 mounted adjacent to the upper end of the cylinder, said set-screw also serving to maintain said tube in adjusted position.

It will be noted that the automatic elevation of the tube 15, as aforesaid, is due to the fact that the discharge of water through the shower ring 22 is prevented by allowing the latter to remain in its suspended position, indicated in dotted lines in Fig. 1, wherein the passage of water through the hinge valve 20 is cut off. Said hinge valve is of that type wherein is employed a pair of similar pivotally connected members having flat engaging faces forming a ground joint, one of said faces being adapted for rotary movement upon the other, and said faces are provided with ports adapted to be brought into and out of registration for respectively permitting and cutting off communication between said members. In the present case a pair of ports 29 in the face of the movable member of the valve are adapted to be carried into register with similar ports 30 provided in the contacting face of the stationary member of the valve 50 when the tubular ring-carrying arm 31 occupies its extended or horizontal position. The pivot pin 35 connecting the members of said hinge valve preferably has wings 36 on its outer end whereby it may be adjusted 55 to frictionally secure said members against rotation.

A dial 32 is preferably provided at the outer end of the control valve 13, the same

having indicated thereon the position to which an indicator 33 carried by the operating stem 34 must be turned to cause the valve to perform its various functions.

While I have described in detail a preferred form of my invention, it is to be understood that various changes may be made in the form and arrangement of the parts without departing from the spirit or scope of the invention as defined in the appended claims.

What is claimed is—

1. The combination with a bath cock, of an upright tube coupled to said cock, an upright cylinder connected to the upper end of said tube; a pipe of materially less diameter than said cylinder telescoped within the upper end of the latter, a piston encircling the lower end of said pipe and movable within said cylinder, said piston preventing withdrawal of said pipe from said cylinder, a hinge valve having one arm connected to the upper end of said pipe, and a shower ring connected to the opposite arm of said valve, said ring being adapted to swing from a suspended position to a horizontal position, and vice versa, respectively opening and closing said valve, said piston and superposed connected parts being automatically elevatable under the pressure of water admitted to the cylinder when said ring occupies suspended position.

2. In a shower attachment for bath tubs, the combination with an upright cylinder and means connecting said cylinder with a bath cock, of a pipe partially disposed within and having vertical movement with respect to said cylinder, a piston disposed about the lower end of said pipe and preventing withdrawal of said pipe from said cylinder, the upper end of said pipe extending above the top of said cylinder, a shower ring, a hinge valve connecting said shower ring to the upper end of said pipe, said ring being adapted to be swung from a suspended to a horizontal position, and vice versa, respectively opening and closing said valve, said piston and superposed connected parts being automatically elevated under the pressure of water admitted to the cylinder when said ring occupies suspended position.

In testimony whereof, I affix my signature in presence of two subscribing witnesses.

PETER SELTNER.
